UNITED STATES PATENT OFFICE.

FRANCES M. HASKINS, OF NEW YORK, N. Y.

BABY EXERCISER.

1,426,063.

Specification of Letters Patent. Patented Aug. 15, 1922.

Application filed September 20, 1921. Serial No. 501,930.

To all whom it may concern:

Be it known that I, FRANCES M. HASKINS, a citizen of the United States, residing at New York city, in the county of New York and State of New York, have invented certain new and useful Improvements in Baby Exercisers, of which the following is a specification.

This invention relates to appliances for 10 the care, entertainment, exercise, or physical culture of babies and especially young babies, who otherwise are usually either left to themselves, or else are put under the care of nurses, unless the mothers are willing to 15 give them the personal attention that they should have. It is well known that babies three or four months or age or upward, if normal and healthy, possess a considerable amount of vitality which for the sake of the 20 infants should be so directed as to be exercised along beneficial lines, and moreover normal active babies of such ages are very much more wearing upon their mothers than the mothers realize or are oftentimes willing 25 to admit.

Among the objects of this invention therefore is to provide an apparatus, termed herein an exerciser, for the accommodation of a baby of three or four months or upward, 30 into which the baby may be placed with not only utmost impunity and safety but moreover in which it will not only be most satisfactorily entertained through its own efforts but will be properly exercised and developed, it being my experience that a baby so placed and left to its own resources will exercise beautifully and happily for hours at a time or until it becomes naturally weary and desires to go to sleep.

40 I am aware that it is not broadly new to provide a hanger or sling in which a baby is presumed to be suspended for the same general purpose as set forth herein, but among the specific and new objects of this 45 improvement is to provide a structure including a sling or body portion that will possess facilities for the utmost safety and comfort to the baby, especially with respect to a full rounded seat or hip-engaging portion, but without hampering or restricting 50 the legs, leaving them free for natural activity.

Another object of the invention is to simplify and improve the means for attaching 55 the sling to the child with utmost safety and

also adaptability for adjustment according to its size or development.

A still further object of the invention, distinguishing it from previous attempts along this line, is to provide improved overhead 60 hanger means along the lines of adjustment as to height, facility for attaching or detaching the infant from the overhead support, and improved spreader means for the 65 suspension device.

With the foregoing and other objects in view the invention consists in the arrangement and combination of parts hereinafter described and claimed, and while the invention is not restricted to the exact details of 70 construction disclosed or suggested herein, still for the purpose of illustrating a practical embodiment thereof reference is had to the accompanying drawings, in which like reference characters designate the same 75 parts in the several views, and in which—

Figure 1 is a perspective view indicating the manner of use of the improvement.

Fig. 2 is an enlarged view, parts in section, showing more particularly the details 80 of the device.

Fig. 3 is a plan view of the sling mainly in flat position.

Fig. 4 is a horizontal section on about the plane of the line 4—4 of Fig. 2, but with 85 parts omitted to avoid confusion.

Referring now more specifically to the drawings I show my improvement as comprising an overhead support 10 including an adjustable strap 11, a bridle 12, and a 90 sling 13.

The overhead support comprises one or more, preferably two, coil springs 14 adapted to be permanently connected as by means of a ring or hook 15 to the ceiling, door 95 lintel, or other suitable arch represented at 16. To the lower end of the spring is connected a ring 17 through which the strap 11 is passed, and to the lower portion of the strap is secured another ring 18, the effective length of the strap between the rings being determined according to the height of the arch, the length of the lower portions of the device, and the size of the baby. The strap as shown is provided with a buckle 19 100 of any suitable construction to take care of the adjustment of the strap as to length.

The bridle comprises two straps 20 lead from the sling upward past the spreader comprising two rods or bars 21, thence 110

through a keeper 22, and through the loop 23 of a swivel hook 24 detachably engageable with the ring 18. Then each strap passes downward again through the keeper 5 past the spreader to the diametrically opposite portion of the sling from its starting point. As indicated, considering the sling as circular or oval in plan view, the ends of the straps 20 are attached in any suitable 10 safe manner to the upper or band portion 25 of the sling at about 90° apart so as to distribute the strain about equally upon all quarters of the sling. The keeper 22 is essentially a rectangular piece of metal with 15 two parallel slots through which the straps pass. This keeper is adapted to be moved by hand along the upper portions or loops of the straps so as to occupy any desired position between the swivel and the spreader. 20 For ordinary purposes or while the device is in use the keeper is preferably moved up close to the swivel so as to prevent the slipping of the straps through the loop 23 while the child is playing or exercising, but when 25 the device is taken down from the overhead support I deem it best to slide the keeper downward as far as it will go toward the spreader so as to make it impossible for the straps to become tangled with respect to 30 each other and the spreader. The spreader comprises two bars or rods, made preferably of heavy round wire and each formed at its ends with loops 21' of substantially triangular form. Any suitable means may 35 be employed to attach the spreader rods to the straps 20. To this end I employ keepers 26 similar to the keeper 22 in that each is provided with two parallel slots through one of which slots the strap 20 passes and 40 through the other of which slots a loop 27 of the same strap is passed, and in this loop the outer leg portion of the triangular loop 21' of the rod lies. When the strap 20 is thus drawn taut the loop 21' will be 45 drawn snugly against the inner surface of the adjacent keeper 26, and hence the spreader rods and keepers 26 will be so retained at any desired elevation, this holding being effective through friction and is 50 quite sufficient to maintain the spreader at any desired point along the straps. It is easy however for the spreader to be adjusted either up or down if necessary simply by loosening the straps at the keepers. The 55 central portions of the spreader rods are loose and simply cross each other loosely and freely thus adapting the spreader for automatic accommodation of itself and the straps according to the strain brought upon 60 the lower ends thereof and leaving the child's arms and head unobstructed. While a child is exercising actively the bars are subjected to a more or less constant relative movement, both longitudinally and scissor-fashion. The purpose of the swivel is

to provide for rotation of the child around a vertical axis, without the accompanying twisting of the straps.

The sling comprises a body portion 28 extending across the lower portion of the child's back and well beneath the hips, forming a seat portion 29 which extends far enough downward and forward to come beneath the hip joints and so make a seat, that is not only comfortable to the baby but 70 practically safe considering the fact that the device is adapted for and has been successfully used in connection with babies hardly over three months of age. The body portion 28 is fixed in any suitable safe manner to the belt 25 to which the straps 20 are secured. To one end of the band 25 is secured a wire loop 30 having detachable engagement with an adjustable button 31 secured at any desired point at another portion of the band. These buttons 31 are preferably of the threaded shank and head structure, a well known form of button, the shank being pointed for slipping or plunging directly through any suitable part of the fabric, and the head is then put upon the shank. The head can be removed however only by unscrewing it from the shank. Adjacent to the fastener 31 are two other buttons 32, preferably of the same type as the buttons 31, and co-operating with these buttons 32 are wire loops 33 on a pair of crotch straps 34 which extend forward between the baby's legs and upward toward the belt, as clearly shown in Fig. 2. These buttons may easily 100 be adjusted as may be required but preferably in line with the straps 20. It may be stated at this time that in putting the baby into the sling the sling is laid out flat as in Fig. 3 on any convenient support such as 105 a bed, crib, or table, the hook 24 being at such time detached from the ring 18. With the device once fitted to the child as to size the operation is exceedingly simple, easy, and safe. The band 25 is first brought 110 around the baby's waist and the loop 30 fastened to its button 31. The crotch straps are then brought up and fastened as indicated in Fig. 2. Finally the hip straps 35 extending laterally from the seat portion 115 29, are brought up around the baby's hips and fastened to each other as by means of a loop 36 carried by one of the hip straps and with an adjustable button 37 on the other hip strap. The baby thus harnessed is 120 then lifted and the swivel hook 24 is snapped into the ring 18, leaving the baby suspended with its toes about touching the floor, and with the springs 14 under extension proportional to weight of the baby suspended 125 therefrom. The weight of the baby is supported primarily and directly upon the seat 29 of the sling, and the sling is supported directly from the overhead support through the straps 20 and hook, the baby's center of 130

gravity being well below the points of attachment of the straps to the waist band. The hip straps 35 render it impossible for the baby to slip from the seat 29, and the 5 crotch straps 34 support the front portion of the seat directly from the waist band and hanger straps, while all of these portions suitably support the baby's body from twisting or bending to an extent great 10 enough to be injurious.

With the baby harnessed and suspended as indicated it soon acquires the ability to amuse and exercise itself, first by contact of its toes with the floor, causing the springs 15 to play up and down, but leaving the baby's arms and legs free for active movement. After the brief period of exercise with the up and down movement the baby soon acquires the ability to oscillate itself laterally. 20 The spreader rods, in addition to keeping the straps 20 well spaced from each other and from the baby, serve to reduce to a minimum the possibility of the baby causing itself to be struck against the side of the door 25 or other fixed object while exercising. When the baby is removed from the overhead support it is only necessary for the hook to be removed from the ring 18, which may be hung low enough to be easily reached 30 by any adult person, and then the keeper if moved downward toward the spreader will bring the spreader portions close together and hold them in relatively fixed position. The baby is then laid on its back and the 35 various connections separated as will be understood. The straps and sling may then be rolled up for storage in any convenient place or if desired may be snapped again upon the ring 18 until again to be used.

40 I claim:

1. In a baby exerciser, the combination of a sling for the immediate support of the baby, overhead supporting means including a loop, and a bridle extending between the 45 sling and the loop, said bridle comprising

a plurality of straps attached to the sling and slipped through said loop, a pair of independent spreader rods connected to said straps between the sling and the loop, said rods being freely movable relative 50 to each other in every direction, and a keeper embracing the portions of the straps at the loop and normally holding the straps from movement through the loop but movable directly along the 55 straps to a position adjacent to the spreader rods to prevent the tangling of the bridle when the device is not in use.

2. In a baby exerciser, a sling comprising a flexible seat portion extending well forward beneath the baby's hips and shaped to fit the body so as to leave its legs perfectly free and unobstructed and extending also upward to its waist line, a waist band attached to the portion having the seat, a pair 60 of crotch straps extending forward and upward from the seat to the waist band, and a pair of hip straps extending laterally and forward around the hips and adapted to be connected to each other at the front. 65

3. A device as set forth in claim 2 in which the several connections of the sling portions are effective by means of separable buttons adjustable along the fabric and co-operating with loop members fixed to certain 70 of the parts. 75

4. In a baby exerciser, the combination of a sling for the immediate support of the baby, overhead supporting means including a loop, and a bridle extending between 80 the sling and the loop, said bridle comprising a plurality of straps attached to the sling and slipped through said loop, and a pair of independent spreader rods connected to said straps between the sling and the 85 loop, said rods being freely movable relative to each other in every direction.

In testimony whereof I affix my signature.

FRANCES M. HASKINS.
